FLASHLIGHT-ILLUMINABLE SLIDE PROJECTOR

Luther A. Blackburn, Eagle Rock, Calif.

Application March 31, 1959, Serial No. 55,274

Term of patent 14 years

(Cl. D61—1)

Fig. 1 is a side elevational view of a flashlight-illuminable slide projector, showing my new design, the opposite side being substantially a mirror image thereof,

Fig. 2 is a perspective view,

Fig. 3 is a top plan view,

Fig. 4 is a front elevational view, and

Fig. 5 is a rear elevational view thereof.

The broken lines showing of a representative flashlight in Figs. 1 and 3 is for illustrative purposes only.

I claim:

The ornamental design for a flashlight-illuminable slide projector, substantially as shown and described.
